CLAIM

The ornamental design for a partitioning device, as shown and described.

DESCRIPTION

FIG. 1 is a left side perspective view of the partitioning device of the present invention.

FIG. 2 is a right side perspective view of the partitioning device of the present invention.

FIG. 3 is a front elevation of the partitioning device of the present invention.

FIG. 4 is a rear elevation of the partitioning device of the present invention.

FIG. 5 is a left side elevation of the partitioning device of the present invention.

FIG. 6 is a right side elevation of the partitioning device of the present invention.

FIG. 7 is a top view of the partitioning device of the present invention.

FIG. 8 is a bottom view of the partitioning device of the present invention.

FIG. 9 is a left side perspective view of the partitioning device of the present invention in an open configuration in an on-seat environment.

FIG. 10 is a right side perspective view of the partitioning device of the present invention in an open configuration in an on-seat environment.

FIG. 11 is a front elevation of the partitioning device of the present invention in an open configuration in an on-seat environment.

FIG. 12 is a rear elevation of the partitioning device of the present invention in an open configuration in an on-seat environment.

(Continued)

FIG. 13 is a left side elevation of the partitioning device of the present invention in its open configuration in an on-seat environment.

FIG. 14 is a right side elevation of the partitioning device of the present invention in an open configuration in an on-seat environment.

FIG. 15 is a top view of the partitioning device of the present invention in an open configuration in an on-seat environment.

FIG. 16 is a bottom view of the partitioning device of the present invention in an open configuration in an on-seat environment.

FIG. 17 is a left side perspective view of the partitioning device of the present invention in a closed configuration in an on-seat environment.

FIG. 18 is a right side perspective view of the partitioning device of the present invention in a closed configuration in an on-seat environment.

FIG. 19 is a front elevation of the partitioning device of the present invention in a closed configuration in an on-seat environment.

FIG. 20 is a rear elevation of the partitioning device of the present invention in a closed configuration in an on-seat environment.

FIG. 21 is a left side elevation of the partitioning device of the present invention in a closed configuration in an on-seat environment.

FIG. 22 is a right side elevation of the partitioning device of the present invention in a closed configuration in an on-seat environment.

FIG. 23 is a top view of the partitioning device of the present invention in a closed configuration in an on-seat environment; and,

FIG. 24 is a bottom view of the partitioning device of the present invention in a closed configuration in an on-seat environment.

The broken lines in the drawings are for the purpose of illustrating the environment of the present invention and form no part of the claimed design.
